Attorney

UNITED STATES PATENT OFFICE.

FINN J. BRONNER, OF BRADFORD, PENNSYLVANIA.

DENTAL INSTRUMENT.

Application filed June 4, 1923. Serial No. 643,312.

To all whom it may concern:

Be it known that I, FINN J. BRONNER, a subject of the King of Norway, and resident of Bradford, in the county of McKean 5 and State of Pennsylvania, have invented certain new and useful Improvements in Dental Instruments, of which the following is a specification.

This invention relates to dentistry, and 10 particularly to a hollow drill adapted for use in penetrating bone structures such as the jaws or mastoid processes of a patient in order to provide drainage (in abscesses) or to inject anæsthetics or other fluids into 15 the nerve canals or interior structure of the bones where such internal treatment is desired.

It is an object of this invention to produce a device which can be operated by a 20 dental engine as an auxiliary to the hand pieces of such dental engine; and the said invention comprises what might be termed a chuck to which a hollow drill is connected, the said device being associated with novel 25 means for preventing fouling of the passage in the hollow drill through which suction or drainage can be established or the medicated fluid is to be forced after the drill has cut its way into that part of the anatomy 30 to be treated, drained or anæsthetized.

It is a further object of this invention to produce a hollow drill or needle such as is employed for hypodermic injections and the like, associated with novel means for preventing cuttings from entering the orifice in the drill or needle; the said device being intended to be employed in association with a syringe or liquid forcing agent whereby the medicated liquid will be injected to the point 40 where local treatment is desired.

With the foregoing and other objects in view, the invention consists in the details of construction, and in the arrangement and combination of parts to be hereinafter more 45 fully set forth and claimed.

In describing the invention in detail, reference will be had to the accompanying drawings forming part of this invention wherein like characters denote corresponding 50 parts in the several views, and in which—

Figure 1 illustrates a view in elevation of a device embodying the invention illus-

trated as associated with a hand piece of a dental engine and a liquid forcing device; 55

Figure 2 illustrates a sectional view of the said device;

Figure 3 illustrates a sectional view showing the parts in different positions of adjustment; 60

Figure 4 illustrates a sectional view on a line corresponding with the line 4—4 of Fig. 3;

Figure 5 illustrates a view in elevation partly in section, showing a device applied 65 as an attachment for a hypodermic apparatus;

Figure 6 illustrates a view in elevation of said device; and

Figure 7 illustrates a view in elevation of 70 the handle and cleaner embodying a slightly modified construction.

In these drawings, 10 denotes an ordinary hand piece of a dental engine, and 11 a liquid forcing device, such as a syringe, that 75 are conventionally shown and need not be described in detail. The attachment comprises a shank 12 that is applied to the hand piece, although any other suitable means may be provided for its rotation; 80 and the said shank extends into a cylinder 13 through the aperture 14 of a removable head 15, which head is preferably threaded in place. The shank has an annular flange 16 seated at the end of the cylinder, and a 85 packing 17 is interposed between the flange and the inner wall of the head to prevent leakage when the device is in operation.

The shank extends through an opposite head 18 on the cylinder, and the said shank 90 has an apertured plug 19 frictionally retained in the end of the said shank, the said plug constituting an anchorage for the cleaning pin 20 that is used for preventing the accumulation of foreign substances in 95 the hollow drill, as will presently appear. The plug has a plurality of longitudinally disposed grooves 21 in its outer surface that form clearances or channels for the passage of the medicated fluid which is to be injected through the hollow drill into the cavity to be treated. That portion of the shank within the cylinder has a longitudinally disposed slot 23 in which a pin 24 is 100 slidable, the said pin being anchored to the head 25 of a tube 26 that is slidable through 105

the head 18 to the position in which it is shown in Fig. 2, or to the position in which it is shown in Fig. 3.

The tube 26 may be externally threaded 5 as at 27, and a hollow drill 28 may be threaded on the said tube.

A suitable connection 29 may communicate with the interior of the cylinder, and the said connection 29 may be employed for 10 the attachment of the syringe 11 or injector by which medicated fluid is forced into the cylinder. Any suitable connection may be employed as a means for effecting communication of the source of medicated fluid 15 with the cylinder, and the inventor does not wish to be limited with respect to these details, but, as illustrated, when the syringe is applied to the connection and fluid is forced into the cylinder, it will result in moving 20 the parts of the positions in which they are shown in Fig. 3 of the drawing.

During the drilling operation and when pressure is being applied to force the drill through the structure being drilled, the 25 parts will assume the position shown in Fig. 2, but after the hand pressure incident to the drilling operation has been removed and the injector is operated, the force or pressure incident to the injecting of the fluid 30 will force the cylinder outwardly with respect to the tube 26 and cause the withdrawal of the cleaning pin from the interior of the hollow drill to permit the flow of fluid through the drill. By reason of the 35 fact that the cleaning pin is within the drill during the drilling operation, the duct through the drill cannot be fouled by the accumulation of cuttings or the like, and hence the force necessary for delivering the 40 medicated fluid to the cavity to be treated will be minimized.

In that form of the invention shown in Figs. 5, 6, and 7, a hollow needle 30 is in communication with a head 31 having a 45 socket 32 into which medicine may be poured and it is also adapted to receive the shank 33 of a handle 34. The handle 34 has a cleaning pin 35 that extends into the needle, and the relation of parts shown in 50 Fig. 5 is maintained during the insertion of the needle. After the needle has been inserted, the shank of the handle is removed from the socket of the head and the cleaning pin is withdrawn from the interior of the 55 needle. The socket is such that a fitting may

be applied to it, through which medicated fluid may be injected from a suitable syringe or the like.

Figure 7 illustrates a modified construction in which the shank 36 of the handle 37 is threaded, and when this is employed, the socket of the head shown in Fig. 5 would be threaded to engage the threads of the shank. The cleaning needle 38 of the form shown in Fig. 7 is of the same general type 65 as that heretofore described, and the only difference between the device of Fig. 7 and that of Fig. 5 is that provision is made for a more secure connection between the shank of the handle and the socket of the 70 head. In the form shown in Fig. 5, the relation of the handle and the head is maintained by friction.

I claim:

1. In a hollow medicated liquid applying device, a hollow penetrating instrument, a tube to which the instrument is connected, a cylinder slidably applied to the said tube, the said tube and cylinder having means of communication, a cleaning pin stationary 80 with relation to the instrument rotating means, and means whereby medicated fluid is delivered to the interior of the cylinder.

2. In a hollow medicated liquid applying device, a cylinder, a shank rotatably 85 mounted therein having a longitudinally disposed slot, a tube extending into the cylinder, means for connecting the shank to the said tube whereby they rotate in unison, a cleaning pin carried by the shank, a hollow 90 penetrating instrument secured on the tube and rotatable therewith, the said tube and shank having means of communication, and means for supplying medicated fluid to the cylinder.

3. In a hollow medicated liquid applying device, a rotatable member adapted to be driven by an engine, a member slidable thereon and rotatable therewith, means of communication between the two members, 100 a cleaning pin carried by the first mentioned member and extending into the second mentioned member, a hollow penetrating instrument carried by the second mentioned member and communicating therewith and movable with relation to the cleaning pin, and means for supplying fluid to the said members.

FINN J. BRONNER.
